COMBINED PIPE CLOSURE DISK AND SEALING RING

Arthur E. Kaiser, Seattle, and Jefferson M. Fluke, Kirkland, Wash., assignors to Kaiser Seal Company, Inc., Bothell, Wash., a corporation of Washington

Filed May 15, 1967, Ser. No. 7,119

Term of patent 14 years

(Cl. D23—41)

FIG. 1 is a perspective view of a combined pipe closure disk and sealing ring, substantially as shown.

FIG. 2 is a top plan view thereof;

FIG. 3 is a bottom plan view;

FIG. 4 is an elevational view; and

FIG. 5 is a sectional view on line 5—5 of FIG. 2.

We claim:

The ornamental design for a combined pipe closure disk and sealing ring, substantially as shown.
